STRUT CATHODE SUPPORT

William R. Wheeler, Wantagh, N. Y., assignor to Sylvania Electric Products Inc., a corporation of Massachusetts

Application April 19, 1954, Serial No. 424,226

3 Claims. (Cl. 313—289)

This invention relates to electronic tube structure and particularly to the means for mounting the cathode in proper position relative to a grid and anode.

In the manufacture of stack tubes, i. e., those employing planar elements which are sandwiched together, difficulty has been found in fixing the elements in proper spaced relationship to one another. In the case of a heated cathode, where one is employed, and where parts are very closely spaced an additional problem arises due to the expansion of the cathode when heated. Provision must be made for such expansion and yet in a direction to not materially affect the spacing between elements, as between the cathode and grid. Another problem is to properly support the cathode and yet prevent excessive heat conduction away from the cathode through its support. Furthermore the structure of the tube should be simple to allow for ease in manufacture.

It is an object of this invention to provide, in a sandwich type tube mount, a simple support means for the cathode.

It is a further object of this invention to utilize the support means as a suitable spacer between the cathode and grid.

It is yet another object of the invention to still further utilize the cathode support means as a medium to clamp the parts of a tube mount together.

Further objects will become apparent after reading the following specification in the light of the accompanying drawings in which:

Fig. 1 is an end elevation of an electron tube mount in a position on a tube base.

Fig. 2 is an enlarged view of a composite electrode utilized in the mount, parts being sectioned away, and

Fig. 3 is an exploded view of the assembly of Fig. 1.

Referring to the drawings more in detail, at 10 there is shown a tube base, or stem preferably of ceramic material such as alumina, having pin leads 12 embedded therein, on which the mount is secured.

The mount here illustrated is a double triode comprised of a cathode sleeve 16 and two grid-anode structures 18. The cathode sleeve is of the rectangular sleeve type with emissive surfaces 20 on opposite faces of the cathode. Within the sleeve is the heater 22 suitably tabbed, as at 24, with the tabs welded to two of the stem leads.

Each of the grid-anode structures comprises a rectangular ceramic wafer 26 preferably of zircon with a recess 28 extending inward from one face 30 of the ceramic. The bottom only of the recess and the face 30 are coated with an electro-conductive material such as a film of moly-manganese 31 (e. g. 80 parts molybdenum, 20 parts manganese) and integrally associated with the outer coated face is a grid structure, here shown as made of tungsten wires 32. To reduce leakage between the grid structure and the coating on the bottom of the recess, the ceramic is slotted longitudinally at 34, walls of the slits being prolongation of side walls of the recess and the end portions of the recess are deepened and enlarged as at 35 to increase the resistance between coatings 31. The bottom coating is electrically secured to pins 36 passing through the ceramic. The bottom coatings form anodes of the tube structure. The grid is provided with a conducting tab 38 of molybdenum or the like brazed to the grid surface and appropriately welded to a lead 12.

2

In order to mount parts in suitable spaced apart but fixed relationship and yet permit proper expansion of parts of the mount, there is provided a pair of sheet metal straps 40, one near each end of the mount. The straps are precision stamped to shape and size and are of a thin metal having low thermal conductivity. Each stamping has two parallel runners 42 and a bridge 44. The bridge has an offset portion 46 in the plane of the bridge centrally of the length of the bridge. The distance between the outside edge 48 of the offset portion and the opposed edge 50 of the bridge is equal to the spacings of the ceramic wafers from one another and the offset in the bridge is designed to space the cathode equally from each grid. To secure the cathode sleeve on the bridges with minimum heat transfer, the bridges at the recessed portions are edge welded to the sleeves as at 52. To clamp the assembly together the free ends of the runners are bent around the outside faces of the ceramic wafers 26, preferably while heating the runners as by placing the electrodes of a welding machine across opposite ends of a runner. While the strap is still hot, the runner ends can be bent around the wafers 26. The runners are tight enough about the wafers to prevent separation of parts yet loose enough to allow slippage of a strap on heating and cooling of the cathode with consequent expansion and contraction thereof. With a rectangular cathode very little expansion takes place in the direction of the grids. Therefore, the tube constants are suitably maintained through the range of operating temperatures of the tube.

Selected leads are surmounted by plates 54 to which the pins 36 are welded and a getter 56 is provided on the mount, thus completing the assembly.

Having thus described my invention what is claimed as new is:

1. A support element for a stacked tube comprising a sheet metal member having two parallel equal rectangular runners and a bridge therebetween substantially midway of the length of the runners, the bridge having an offset portion in the plane of the bridge substantially midway of the length of the bridge.

2. A stacked tube mount comprising an electrode, a cathode sleeve and a support member of thin sheet metal, said support member having a pair of parallel runners and a bridge between the runners, the cathode sleeve being secured to an edge of the bridge and the runners having bent portions embracing the electrode, the width of the bridge between the edge which the cathode sleeve is secured and the contact of the bridge with the electrode determining the spacing of the cathode sleeve from the electrode.

3. A stacked tube mount comprising a pair of electrodes, a cathode sleeve, rectangular in cross section, and a support member of thin sheet metal, said support member having a pair of parallel runners and a bridge between the runners, the bridge having an offset portion midway of its length, the cathode sleeve being secured to the bridge member at said offset portion to an edge of the bridge, the planes of the opposite edges of the bridge being spaced apart a distance equal to the desired spacing of the electrodes, with the faces of the cathode sleeve lying within and equal distances from said planes, the runners having their free ends embracing the electrodes.
